PACKAGE

Philip O'C. White, Chicago, Ill., assignor to White Cap Company, Chicago, Ill., a corporation of Delaware

Application November 10, 1938, Serial No. 239,845

2 Claims. (Cl. 215—40)

This invention relates to packages or packing containers of the type wherein a receptacle, such as a jar or bottle, is closed and hermetically sealed by means of a closure cap which is forced to sealing position on the receptacle by downward pressure.

In the packaging of various commodities, such as catsup or other sauces, which are quite generally dispensed from the original receptacles at the table, it is quite important that the package be hermetically sealed in the first instance, so that the contents will be properly preserved against contamination and fermentation, and that it be susceptible to re-sealing with facility to prevent evaporation or leakage after it has been opened initially. Also, it is of importance, for protection of the material against contamination or evaporation after the package has been opened by the user, that the closure be of a character such that it may be removed and replaced with facility incident to the dispensing of a portion of the material, and that when it is replaced, it effectively cover the mouth of the receptacle and stay in place with sufficient certainty or security to permit the receptacle to be handled freely. It is quite generally observed that very little care is exercised by users in replacing the closure after pouring out some of the material, and that if the operation of putting it back on requires the exercise of any particular accuracy or effort, it is usually left off or applied improperly and insecurely.

It is one of the general objects of the present invention to provide a package or packing container which is stoppered by means of a closure in the nature of a cap, and which is of a character such that, in the first instance at least, it may be sealed on the receptacle hermetically and very securely by simple downward pressure which may be accomplished rapidly by automatic machinery, and which may be removed with facility in the first instance and thereafter re-applied with very little effort to re-seal the receptacle air tight, or to form an effective closure and protection for the mouth of the receptacle and retain its place thereon with adequate security although not re-sealed air tight thereon.

Another object is the provision of a package or packing container of the character specified and wherein the closure, in the nature of a metal cap or the like, is effectively safeguarded against scratching or abrasion by the mouth of the vessel incident to the operation of applying or sealing it thereon in the first instance, or subsequently, thus protecting the metal of the cap

shell against oxidation and the mouth of the receptacle against discoloration or fouling which ordinarily results from such oxidation of a metal cap.

Other and further objects of the invention will be pointed out or indicated hereinafter, or will be apparent to one skilled in the art upon an understanding of this specification or employment of the device in use.

For purpose of aiding in an explanation of the invention, I show in the accompanying drawing forming a part of this specification, and hereinafter describe, certain embodiments of the invention in a package and packing container in the nature of a capped bottle or the like, such as may be suitable for the packaging of catsup or sauces. It is to be understood, however, that these examples are here presented merely for purpose of illustration and are not to be construed in any fashion for the purpose of limiting the appended claims short of the true and most comprehensive scope of the invention in the art.

In said drawing

Fig. 1 is a vertical section of the upper portion of a packing container showing the closure in place on the receptacle in the relationship wherein the package is hermetically sealed;

Fig. 2 is a similar section showing the closure cap in place on the receptacle but in a relationship wherein there is no compressed sealing between the two;

Fig. 3 is a vertical section of one form of closure cap which may be employed in the invention, showing same on an enlarged scale;

Fig. 4 is an elevational view of the mouth or upper portion of a receptacle, in the nature of a bottle, showing one form of contour or finish of the parts which may be employed in the package embodying the invention; and

Fig. 5 is a section similar to Figs. 1 and 2 but showing the closure in a canted position on the receptacle, and serving to illustrate the fashion in which the two cooperate to prevent abrasion of the interior surfaces of the closure shell by the mouth portion of the receptacle.

The nature of the invention will be most quickly ascertained from a detailed description of the embodiments shown in the drawing, which is as follows.

The reference numeral 10 designates a receptacle, in the nature of a bottle, jar or the like, suitable for the packaging of various materials which it may be desired to seal and preserve in air-tight condition in the first instance and dis-

pense a portion at a time after the initial opening of the package. This receptacle has mouth portions specially formed for definite purposes in cooperation with a suitable closure. As illustrated more fully in Fig. 4, the mouth portion of the receptacle is formed or finished with a peripheral sealing surface 11, of approximately cylindrical form, extending completely around the receptacle and disposed at a suitable elevation above a peripherally outstanding shoulder or ledge 12. Portions of the material between the sealing surface 11 and ledge 12 are recessed or undercut, as at 14, to form a peripheral groove or channel. From the upper limit of the cylindrical sealing surface 11, the periphery of the container is offset inwardly and upwardly in the form of a rounded or beveled shoulder 15, and, from the limit of this shoulder portion, the periphery of the container continues upwardly as an approximately cylindrical lip portion 16, which is of substantial height, materially exceeding the height of the sealing surface 11, and rounded or beveled inwardly at its upper terminus at 17, to the top rim 18 of the receptacle mouth. All of said peripheral surfaces are substantially circular on planes perpendicular to the axis of the receptacle mouth.

A closure cap suitable for sealing cooperation with the vessel mouth is provided, and may be of the form illustrated in Fig. 3. This includes a shell, which may be pressed from sheet metal, such as tin-plate, having suitable ductility and the proper stiffness to hold its shape in use, and which is formed with a top portion 20, of circular contour, and depending skirt portion 21 extending downwardly from the periphery of the top portion in approximately cylindrical form and merging into a flaring skirt portion 22 toward the lower end. This shell is of sufficient diameter to accommodate the portions of the receptacle above the ledge 12 with a clearance, and is of sufficient depth to receive the lip portion 16, sealing surface 11, and upper part of the undercut portion 14, but not to reach to the ledge 12 when the top portion 20 is seated on the receptacle rim 18. Within the closure shell is disposed a gasket 24 which is formed of a suitable elastic and compressible material, such as a good vulcanized rubber composition, and is of sleeve form. This gasket is normally of somewhat larger diameter than the interior of the skirt portion 22, but is circumferentially compressed and inserted into the shell in such position that it rests against the flaring skirt portion 22 and extends slightly within and close to the cylindrical skirt portion 21.

The lower portion of the shell skirt is notched to provide a plurality of serrations or prongs 25, and these are curled inwardly and upwardly and embedded in the lower portion of the gasket, so that it is securely fastened to the shell at its lower end. Due to its form and elastic character and the form of the shell, the orifice of the gasket takes an upwardly contracting or converging shape. The thickness of the gasket materially exceeds the clearance between the skirt portion 21 and the sealing surface 11, and in its lower portion, the gasket is somewhat thickened or fattened by virtue of the intrusion of the prongs 25 into it.

In the original closing of the package, that is, the original sealing of the closure upon the receptacle after the latter has received its contents, and either with or without displacement of air from the unoccupied head space, the closure

is telescoped onto the receptacle mouth so that the lip portion 16 is introduced within the orifice of the gasket. The relative diameters of these parts are such that the lip portion 16 enters freely until the shoulder part 15 contacts the gasket, as illustrated for example in Fig. 2. Then, upon application of sufficient downward pressure to the top of the closure, it is forced further downwardly onto the receptacle, with the result that the elastic gasket is wedged outwardly along the shoulder 15 and the sealing surface 11, and highly compressed between the sealing surface and the skirt portion of the shell. Incident to this operation, the gasket is elongated upwardly somewhat, the downward movement of the closure being finally limited by contact of its top portion against the rim 18 of the receptacle in the position illustrated in Fig. 1.

As a result of these sealing operations, the gasket is very tightly compressed between the sealing surface 11 and against the surrounding portion of the shell skirt, which acts as a constraining member, the gasket thereby forming a hermetic seal between the shell and the sealing surface 11 and, due to its high compression, filling all irregularities in the surfaces of those parts so that a completely air-tight closure is formed. As a consequence, the closure is very securely retained on the receptacle by the frictional and gripping action of the compressed gasket, and the contents of the receptacle are completely protected against contamination or ingress of air, even though the pressure within the head space of the sealed package may be very much below the external atmospheric pressure.

By suitable manipulation, however, the opening of the hermetically sealed package may be accomplished with comparative ease. This is done by placing a prying implement, such as the margin of a coin, the back of a knife or the like, between the lower margin of the skirt 22 and the ledge 12, and prying upwardly against the closure, using the ledge as a fulcrum. The prying pressure may be applied progressively at various points around the package until the closure is moved upwardly enough to release the elastic gasket from compression between the sealing surface 11 and the skirt of the shell, and thereupon the closure may be lifted off quite freely.

The closure may be re-applied in a fashion to form an air-tight seal on the receptacle, by pressing it downwardly thereon with sufficient force to intrude the sealing surface within the gasket, as in the first instance. However, inasmuch as this may require more effort than the average person might be inclined to apply to it at the dining table, I have designed the parts so that the closure may be put back on very easily and simply, in a fashion such that it will form an effective stopper to protect the mouth of the receptacle, in which disposal it will hold its place with sufficient security to permit its being handled with freedom. Such application is accomplished simply by placing the closure on the mouth of the vessel in the position illustrated in Fig. 2. In this operation the lip portion 16 passes through the gasket to a sufficient distance to retain the closure securely against toppling or slipping off, the contact of the upper portion of the gasket with the lip portion 16 affording a certain amount of holding friction. By the exertion of even slight pressure on the top of the closure, the gasket may be forced to a greater or less extent downwardly on the sloping shoulder 15, to create additional binding or holding compression.

One important feature of the construction is illustrated in Fig. 5. Where metal closure caps or shells are used for the sealing of saucers containing acids, such as vinegar, or various other ingredients which are promotive of oxidation of metals, it is necessary that the interior surfaces of the metal shell be coated with a protective covering of lacquer or the like. Even a slight abrasion or breaking of this lacquer may be sufficient to permit access of the oxidizing liquid to the metal, with the result that dark colored oxides may be formed on the inner portions of the shell. When this comes off on the mouth of the receptacle, it forms a displeasing coloration and suggests that the contents may be contaminated.

Such abrasion or scratching of the lacquer inside the shells of closure caps is very likely to occur in the operation of applying or sealing the closures on the receptacles, if portions of the receptacle which enter the shell are permitted to rub against its inner surfaces. The present construction avoids the possibility of such abrasive contact of the receptacle mouth with the shell, by virtue of the fact that the gasket 24 extends inwardly a sufficient distance to function as a limiting buffer which will prevent the canting of the shell to a position where any part of the lip portion of the receptacle will contact the skirt of the shell. This is illustrated in Fig. 5, wherein the location of the closure in the maximum canted position is illustrated in full lines, whence it will be seen that in such relationship the container mouth cannot pass through the gasket, and the farthest canted position in which the mouth can enter the shell is shown in dotted lines, wherein it will be seen that the mouth portion cannot contact the shell skirt.

It will be ascertained from the foregoing that the package is of simple character and may be manufactured economically by customary procedure, and that the parts may be assembled and sealed together by means of automatic apparatus now quite extensively used in the packing industry.

It is also to be observed that the closure, or the receptacle, or both, may be modified in form or in various other particulars without departing from the spirit or character of the invention.

What I claim is:

1. In a packing container, a receptacle having a mouth at its upper end and an approximately

cylindrical peripheral sealing surface of substantial axial extent spaced below its mouth and an annular lip portion of smaller external diameter than said cylindrical sealing surface extending upwardly from the latter to the mouth rim, the periphery of said receptacle being formed with an outwardly sloping shoulder between said lip portion and the upper extremity of said cylindrical sealing surface; and a closure cap shell having a top portion and a depending annular skirt formed with an approximately cylindrical upper part adapted to surround in spaced relation thereto said lip and sealing surface, and a downwardly flaring lower part below said cylindrical upper part; and a sleeve gasket of elastic sealing material extending upwardly in the shell in contracting form along the inner surface of the skirt with its upper end spaced from the top of the shell and its lower end fastened to the lower end of the skirt; the cylindrical part of the skirt being of depth sufficient to receive both the lip portion and a substantial area of the sealing surface of the receptacle when the closure is fully seated on the receptacle, and the portion of the gasket within the cylindrical part of the skirt being of lesser internal diameter than the external diameter of the sealing surface, whereby to permit a substantial area of the gasket to be elastically compressed radially between the sealing surface of the receptacle and the lower portion of the cylindrical part of the skirt when the closure is pressed axially downward on the receptacle and the sealing surface intruded within the gasket, thereby frictionally securing the closure on the receptacle by the constrictive gripping action of the gasket and forming an hermetic seal between them; the lip portion of the receptacle being of diameter and height such as to pass freely through the orifice of the gasket into the cylindrical part of the shell and retain the closure against toppling off of the receptacle when it is resting loosely thereon with the gasket bearing on the sloping shoulder but out of sealing engagement with the sealing surface.

2. In a packing container, a combination as specified in claim 1 and wherein the gasket is of thickness and height sufficient to prevent the inner surface of the shell skirt contacting the lip portion of the receptacle when the closure is in any canted position thereon.

CERTIFICATE OF CORRECTION.

Patent No. 2,364,678.

December 12, 1944.

PHILIP O'C. WHITE.

It is hereby certified that error appears in the printed specification of the above numbered patent requiring correction as follows: Page 3, first column, line 35, strike out the words "enter the shell" and insert instead --pass through the gasket--; and that the said Letters Patent should be read with this correction therein that the same may conform to the record of the case in the Patent Office.

Signed and sealed this 20th day of March, A. D. 1945.

Leslie Frazer
